CONTROL MECHANISM

Ryder Pratt, Kirkwood, Mo., assignor to Missouri
Automatic Control Corporation, St. Louis, Mo.,
a corporation of Missouri

Application March 20, 1948, Serial No. 15,981

7 Claims. (Cl. 175—320)

1

The present invention relates generally to a control device in which a heat-generating apparatus is automatically controlled in response to a demand for heat within a given space.

Further, the invention pertains generally to a receptacle for containing the relays, switches and the transformer of a burner control system, said receptacle being adaptable for mounting on a wall, or the like, at any selected locale, either adjacent or remote from the heat-generating apparatus.

The receptacle is provided with a removable cover, and the relays, switches, and transformer aforesaid are mounted on a panel which is easily insertable and removable from the receptacle when the cover is taken off.

More particularly, the invention is directed to the switch mechanism and the novel manner in which it is mounted on the panel in relation to and in combination with the other elements thereon.

In applicant's pending application, Serial No. 605,863, filed July 19, 1945, now Patent No. 2,486,612, there is described in detail a control circuit of the type referred to above. That circuit is schematically illustrated, and provides a system particularly adaptable to controlling the action of an oil burner.

The principal object of this invention is to provide a novel compact "package" unit having in convenient arrangement a set of control elements employed in connection with a burner, and especially an oil burner. Specifically, it is an object to provide a novel support or base unit of insulating material whereon the ignition switch, the warp switch, the safety warp switch, the safety and scavenger heaters, and the scavenger warp switch of a burner control system may be mounted; means whereby the support may be readily attached to or removed from the removable panel of a wall receptacle; and means associated with the cover for said receptacle whereby the safety warp switch of said system may be manually reset without removal of the cover.

It is a further object of the invention to provide a support and combination of elements that are compact in design, so that all the above specified elements of the control system are assembled in a group, whereby adjustments or repairs, if required, may be made quickly and easily.

Another object of the invention is to provide means on the casing of the receptacle, in cooperation with means on the panel, whereby the latter may be readily positioned on or removed from the receptacle; means on the panel for

mounting the transformer and the relays of said system successively adjacent the switch mechanism support, and means whereby the cover for the receptacle may be maintained in place.

In addition to those enumerated, other objects and advantages of the invention will become apparent or noted in the description to follow, reference being had also to the accompanying drawings which illustrate the preferred form of the invention. In said drawings:

Fig. 1 is a front elevational view of a receptacle incorporating the present invention, the receptacle being portrayed in position on a fragmentary portion of a wall or the like, and in connection with the combustion or stack switch of the system, the stack being in vertical section;

Fig. 2 is an end elevational view of the receptacle as it appears from the right in Fig. 1, the wall on which it is mounted being shown in section;

Fig. 3 is a front elevational view of the receptacle and its contents with the cover thereof in vertical section;

Fig. 4 is a vertical sectional view taken approximately on the line 4—4 of Fig. 1, the view being indicated also by the line 4—4 of Fig. 3;

Fig. 5 is a fragmentary sectional view taken on the line 5—5 of Fig. 4;

Fig. 6 is an enlarged left side elevation of a unitary switch assembly comprising the principal component of the present invention, the assembly being illustrated as it appears when removed from the receptacle;

Fig. 7 is a similar right side elevational view thereof;

Fig. 8 is a top plan view thereof;

Fig. 9 is a vertical sectional view thereof, taken approximately on line 9—9 of Fig. 8;

Fig. 10 is a similar view taken approximately on line 10—10 of Fig. 3, adjacent portions of a panel on which the assembly is mounted being omitted;

Figs. 11, 12 and 13 are horizontal sectional views thereof taken approximately on lines 11—11, 12—12 and 13—13 of Fig. 3, adjacent portions of said panel being omitted;

Fig. 14 is a fragmentary view of a manual reset means, the view being indicated by line 14—14 in Fig. 4; and

Fig. 15 is a diagram substantially incorporating the circuit diagram of said pending application, in addition to schematically embodying other elements included in the present invention.

Description of the control cycle

With particular reference now to Fig. 15, the control circuit will be briefly described, employing the same reference characters that are employed in the previously mentioned copending application to designate the similar parts. The mode of operation will not be described except where it is thought necessary to understand the invention.

Thus, in Fig. 15, as in the drawings on file, there is shown a primary branch having two lines 11 and 12, connected to a suitable source of power and feeding an ignition device 13, and a burner motor device 14 through a relay switch mechanism 15. Electric current to the ignition devices is supplied by the lines 11, 21, 16, the left-hand switch of the relay switch mechanism 15, the line 17, the ignition switch 24, the line 18, the igniter 13, and lines 19 and 12. The circuit for the burner motor includes the lines 11 and 21, the right-hand switch of the relay 15, the line 22, the burner motor 14 and the lines 23, 19 and 12.

The relay switch 15 is illustrated as having two separate switch elements, of which one is connected into the igniter circuit and the other into the burner motor circuit. Both switches are simultaneously operated to closed or open positions by the energization and deenergization of the coils, as will appear, and for immediate purposes may be considered functionally as one switch.

The two switch elements mentioned comprise two relatively fixed contacts 25 and 26 that are respectively engaged by two movable contacts 27 and 28 when the coil mechanism, generally indicated at 31, is energized in the manner to appear. The coil mechanism 31 is in a low voltage circuit that is energized from a transformer 34, having a primary winding 35 connected by wires 36 across the power lines 11 and 12, and a secondary 37.

The low voltage circuit includes several control elements. There is a space thermostat 32, preferably having an anticipating heater 33. There is a combustion switch 51, having a main contact 53, a cold side contact 54 and a hot side contact 61. This control has heat-responsive elements *a* that are subjected to heat of combustion of the burner. In the absence of combustion, the contact 53 is closed with the contact 54. In the presence of combustion, the contact 53 moves over to contact with the contact 61. In moving from the cold to the hot side, the contact 53 makes with the contact 61 before it breaks with the contact 54.

There are the main relay coil 46 and the secondary relay coil 66. The main relay coil is of adequate power to operate both switches 15 from open to closed positions. The secondary coil 66 adds sufficient impedance, when connected in series with the main coil, to reduce the strength of the two coils to between that required to pull the switches closed and that minimum power to hold them closed.

Other control elements include a safety warp switch and a scavenger warp switch. The safety warp switch is generally indicated at 48. The details of this switch will appear later. Suffice it at present to say that it includes a heater 56 that acts upon a thermally-responsive switch element, such as a bimetal, to open switch contacts.

The scavenger warp switch also is a heat relay type of switch having a scavenger heater 63 that

acts upon a heat-responsive element such as the bimetal strip to operate switch contacts. Both the safety warp switch 48 and the scavenger warp switch 58 are opened when their respective heaters attain predetermined temperature values.

The low voltage or secondary circuits for the operation of the relay switch mechanism 15 may be considered as under primary regulation of the room thermostat 32. It will be seen that the secondary 37 of the transformer 34 is connected by a line 42 to the anticipating heater 33 of the room thermostat, which heater 33 is, in turn, connected by a wire 41 to the room thermostat. The room thermostat has a switch blade 75 that is capable of closing with the contact 76. The contact 76 is connected by a line 44 to a terminal R. From this terminal R, a line 59 leads up to the scavenger warp switch 58, the details of which switch will be discussed hereafter. However, the blade of this switch is connected by a wire 57 through the safety heater 56 of the safety warp switch. This heater, in turn, is connected by a wire 55 that leads through a terminal E and reaches the cold contact 54 of the combustion switch 51. The main or center contact 53 of the combustion switch is connected by a line 52 that leads through a terminal F and goes to the safety warp switch. The other side of the safety warp switch is connected by a wire 47 that leads to the main relay coil 46. The other end of this coil is connected by a wire 45 through a terminal 38 and a wire 43 to the other side of the secondary 37.

The wire 59 that leads from the contact 76 of the room thermostat 32, by way of the line 44 and the terminal R, is as already noted connected into the scavenger warp switch 58. It is also connected, as indicated, directly into the scavenger heater 63 of the scavenger warp switch. The other end of this switch is connected by a wire 64 that is connected also to a wire 65. The wire 65 leads to one end of the secondary relay coil 66. The other end of the relay coil 66 is connected by a wire 62 through a terminal L to the hot contact 61 of the combustion switch 51.

Without going into an extended discussion of the cycle of operation of the over-all control, it may be stated briefly that, when the room thermostat 32 becomes excessively cold, it closes the blade 75 against the contact 76. This establishes a circuit from the constantly energized secondary 37 through the wire 42, the anticipating heater 33, the wire 41, the thermostat 32, the wires 44 and 59, the scavenger warp switch, the wire 57, the safety heater 56, the wire 55, the cold side contact 54, the main contact 53 of the combustion switch, the wire 52, the safety warp switch, the wire 47, the main relay coil 46, the wire 45 and the wire 43 back to the secondary. As the combustion switch is on the cold side at the start of any operation, the foregoing circuit can be closed, and the main relay coil 46 energized. When the main relay coil is energized, the switch 15 is closed, whereupon the circuits to the burner motor 14 and igniter 13 are closed by the previously described circuits. Thus, as soon as the room thermostat closes, the burner motor and the igniter begin to operate.

Also, on the low voltage side, the closure of the room thermostat 32 establishes a circuit that energizes the safety heater 56, which begins to heat up and thereby begins a condition that, if continued, would cause the safety warp switch 58 to open, breaking the previously mentioned circuit.

cuit to the main relay coil 46. If combustion takes place prior to the time lapse for which the safety warp switch 48 is set, the heat-responsive element *a* of the combustion switch mechanism will operate to shift the contact 53 to the left, which operation first closes it with the contact 61 and thereafter breaks it from the contact 54.

When this latter action takes place, the room thermostat circuit continues as before through the contact 76, the lines 44 and 59 to the scavenger warp switch 58. So long as the contacts 53 and 54 remain together, the initially described circuit to the main relay coil 46 will be held energized. As soon as the contact 53 closes with the contact 61, there will be an additional circuit from the scavenger warp switch by way of the line 59, which includes the scavenger heater 63, the line 64, the line 65, the second relay coil 66, the line 62, the hot contact 61 and the main contact 53 of the combustion switch, the line 52, the safety warp switch 48, the line 47, the main relay coil 46, the line 45, and the line 43 to the secondary 37, which as already noted is connected to the thermostat 32.

Thus the shift of the combustion switch in response to the existence of combustion holds the burner motor in operation.

When the heater 63 is energized, it causes the scavenger warp switch to open, and also causes the ignition switch 24 to open and to remain open for a cooling period after the heater is de-energized. Opening of the ignition switch 24 deenergizes the igniter 13. Opening of the scavenger warp switch 58 positively breaks the initial circuit through the cold side contact 54 and the heater 56 of the safety warp switch. Hence, the safety warp switch cannot be opened when combustion properly takes place within the allotted time.

As noted, when both of the coils 46 and 66 are energized in series, the relay has sufficient power to hold the two switch blades closed against their relatively fixed contacts. However, it does not have enough force to pull the two switches closed. Hence, whenever the combustion switch is closed with the hot contact 61, and the relay switch is open for some reason such as power failure, they cannot be reclosed to restart the burner motor until the combustion switch has moved back to cold position and the cycle is started over again.

Details of the control mechanism

Referring now to Fig. 1, it is seen that the heat-responsive member *a* of the combustion switch 51 is disposed transversely of the stack *s*. Wires 52, 55 and 62, enclosed within a conduit *c*, lead from a receptacle, generally designated 80, to a housing *h* which contains the contacts 53, 54 and 61. The combustion switch mechanism 51 is preferably of the type described in this applicant's pending application, Serial No. 588,554, filed April 16, 1945, now abandoned.

Also appearing in Fig. 1, and leading from the receptacle 80 to the thermostat 32, is a conduit *d*, enclosing the wires 42 and 44, a conduit *e* enclosing the wires 18 and 22 leading to the ignition and burner motor devices 13 and 14, respectively, and a conduit *k* enclosing the lines 11 and 12 leading to a power source.

The receptacle 80, as shown particularly in Figs. 3, 4 and 5, comprises a rectangular housing open at the front and having a back wall 82, top and bottom walls 83 and 84, respectively, and left and right end walls 86 and 87.

A cover member of substantially U-shaped configuration, comprising a front wall 89, left and right side walls 90 and 91, and top and bottom horizontally extending peripheral flanges 92 and 93, is provided. This cover, when in place, may be securely so maintained by means of a thumb nut 95, engageable with a threaded projection 96 extending forwardly from a bracket 97 within the receptacle, as will appear. A wall or other mounting surface for the receptacle is designated by the numeral 98.

With particular reference to Figs. 1, 4 and 14, a manually engageable button 100 is seen to be horizontally movable in a supporting flanged aperture 101 formed in the front wall 89 of the cover. The button is normally biased outwardly by means of a leaf spring 102 secured at one end to said wall, as at 103, and having a bifurcated extremity 104 at its other end which engages 20 against an enlarged flange portion of said button, as shown.

The leaf spring 102 yieldingly biases the button 100 to the left, as viewed in Fig. 4. Manual pressure applied thereto externally of the casing 25 moves the button to the right, whereby the safety warp switch 48 may be reset when required.

The receptacle casing may be attached to the wall 98 by any suitable means. Preferably, as shown in Fig. 3, the back wall 82 thereof is provided with a plurality of inverted key hole slots 105, which cooperate with screws 106 embedded in said wall. With this arrangement, the entire receptacle and contents may be detached, if desired, without removing the cover, as is understood.

The top wall 83 of the casing is provided with a pair of elongated slots 107 and 108, the end wall 86 with a recess or notch 109 in its forward edge, the end wall 87 with a similar recess or notch 110, and the bottom wall 84 with a series of identical spaced openings 112 through which the conduits *c*, *d*, *e* and *k* pass. As appears in Fig. 4, the left end wall 86 is not coextensive with the top and bottom walls, but terminates as at 113. For reasons to be explained later, the right end wall 87 is approximately one-half as wide.

The panel to which frequent reference has been had is shown in front elevation in Fig. 3. Its general outline is depicted in dot and dash lines in Fig. 15, and it is generally designated by the numeral 114. This panel is metallic and so formed as to comprise a forward wall 116 and an offset rear wall 117 joined thereto by an integral right angularly disposed connecting wall 118.

Depending from and integral with the wall 116 is an extension 119 which is seated within a recess or depression 120 formed in the front face of an L-shaped member, generally designated 121, which is of plastic insulating material, and the purpose of which will be hereinafter set forth.

The panel 114 is permanently secured to the member 121 primarily by a screw 124, and further by a rivet 125 and a pair of rivets 126, which latter likewise fasten the bracket 97 to said panel. It should, therefore, be manifest that the panel 114 and the member 121 may be considered a unitary assembly.

The manner in which this assembly is removably mounted in the receptacle 80 will now appear, attention being directed especially to Fig. 3.

This view illustrates that the forward wall 116 of the panel has formed thereon a lateral projection 128 and a vertical projection 129. Simi-

larly, the offset rear wall 117 has formed thereon a lateral projection 131 and a vertical projection 132.

Obviously, the arrangement whereby insertion of the projections 129 and 132 into the slots 107 and 108, followed by the swinging of the assembly rearwardly until the lateral projections 128 and 131 engage the notches 109 and 110, provides an adequate support for the said assembly.

Since the wall 117 is rearwardly offset relative to the wall 116, the forward edge of the wall 87, in which the notch 110 is formed, lies relatively close to the back wall 82. The offset in the panel is provided to more adequately accommodate the relay assembly 31 and its associated switch mechanism 15. This entire assembly is secured to the panel by means of screws 134. The housing of the transformer 34 is similarly attached by screws 136. Insertion and removal of the panel assembly is facilitated by the provision of an arcuate recess 137 centrally along the top of the panel.

For a purpose to be explained, a rectangular opening 138 is formed in the forward wall 116 of the panel, and an ear 139, provided with a threaded aperture, extends laterally into the opening, as shown particularly in Fig. 5.

The member 121, which, as previously described, is attached to the depending extension 119 of said panel, extends longitudinally across the receptacle from the left end wall 86 to the right end wall 87.

The member 121 serves as a mounting plate for a series of terminals, by means of which the external wiring is connected to the wiring inside the receptacle.

The terminal posts on the plate 121, reading from right to left, are designated A, B, C, D, E, F, L, T and R. The wires entering the receptacle via the openings 112, and the terminal posts to which they are attached, appear clearly in Fig. 3.

The leads from the opposite side of the plate 121 to the various elements on the panel are wires 21 and 36 from terminal A, wire 36 from terminal B, a continuation of wire 22 from C, a continuation of wire 18 from D, wire 55 from E, wire 52 from F, a continuation of wire 62 from L, a continuation of wire 42 from T, and wire 59 from terminal R.

As earlier indicated, the composite switch assembly, shown per se in Figs. 6 through 13, comprises a principal component of the invention. This assembly, generally designated 140, includes a molded support or base 141 of plastic material, the configuration of which is clearly illustrated.

It is seen to include a generally rectangular body portion 143, provided on either side with a laterally projecting flange portion 145. There is also a rearwardly projecting L-shaped flange portion 146 which may be seen to best advantage in Fig. 5. The lower forward edge of the body 143 is notched or cut out, as at 148, and, as shown particularly in Fig. 12, a horizontally disposed aperture 149 is formed adjacent the left margin thereof.

With this arrangement, the assembly 140 may be manually inserted or removed from the opening 138 of the panel wall 116. When in place, with the flanges 145 against the front face of said wall, and the vertical portion of the notch 148 against the rear face thereof, a screw 152 is passed through the aperture 149 into engagement with the aperture in the ear 139. It should, therefore, be obvious that, whereas fortuitous displacement of said assembly is obviated, its re-

moval from the panel, if desired, is a very simple operation.

Reverting now to the support 141, it is noted that, projecting beyond the rear face of its body portion 143, there are seven terminal elements, designated 155, 156, 157, 158, 159, 160 and 161. Each of these terminals is permanently secured, by means of either rivets or screws 163, to the body 143, which, as shown, is either recessed or slotted, or both, as the case may be, to accommodate the base and body portions of said terminals. From an inspection particularly of Fig. 5, it is seen that the lead 17 terminates at and is soldered to the terminal 155, the lead 52 to the terminal 156, and the lead 41 to the terminal 157. To the terminal 158 is soldered one end of the wire 18, to the terminal 159 the ends of wires 55, to the terminal 160 the ends of wires 59, and to the terminal 161 the ends of the leads 64 and 65. The terminals 155 through 161 are also indicated in Fig. 15, so that the elements of the assembly 140, served by the various wires enumerated, should be readily apparent.

The novel construction whereby the switch and heater elements of the assembly 140 are operatively mounted in compact relationship to one another on the support 140 will now be described. With respect to the ignition switch 24, which includes a contact 165 (Figs. 4, 6, 7, 11) at one end of a blade 166, the support is provided with a forwardly projecting boss portion 168, within a groove 169 of which said blade lies, its other end being fastened by one of the rivets 133 to the terminal 155. This arrangement is especially portrayed in Fig. 11.

The ignition switch 24 further includes a contact 172 at the upper end of an angularly contoured blade 173 (Fig. 6), the lower end of which is riveted, as at 174, to a forwardly and then laterally extending portion 175 of the terminal 158. This arrangement is especially portrayed in Figs. 3, 6, 9 and 10.

With respect to the safety warp switch 48, which includes a contact 178 adjacent the lower channel-shaped end 179 of a blade 180, the body 143 is provided with a recess 182 to receive the upper end 183 of said blade. A rivet 163, passing therethrough, through a rigid vertical retaining strip 184, and through the support, connects the blade with the terminal 157.

This construction is seen to best advantage in Figs. 4 and 7, wherein it is also seen that the lower end 179 of the blade terminates in a forwardly extending substantially horizontal portion 185, to which is attached, by rivets 186, a fibrous or other non-conductive member 188, in contact with the button 100 of the reset device.

The switch 48 also includes a contact 190, normally closed with the contact 178, and carried by the free end of a blade 192 secured by rivets 193 to the laterally projecting flange 194 of an auxiliary blade 195.

As shown particularly in Fig. 12, the blade 195 is secured to a forwardly projecting boss portion 198 of the support, by means of the screw 163 which also secures the terminal 156 thereto. The boss portion 198 is formed immediately below the boss 168, as shown. Said terminal 156 includes an offset downwardly extending portion 200, which carries an adjustment screw 201, normally biasing the blade 195 slightly to the left, as seen in Fig. 3. Attention is also directed to Fig. 7 in this connection.

Reverting again to Fig. 12, and considering also Figs. 3 and 10, a screw 203 entering the boss 198, on the side opposite the blade 195, secures to the

boss, reading from right to left, a bimetallic strip 205, a pad of insulation 206, a non-conductive strip 207, another pad of insulation 208, and finally a non-conductive strip 209.

To the lower end of the bimetal strip 205 is riveted a depending strip 212 of fibrous material, which normally overlies the tip 213 of the blade 192, to bias the latter rearwardly, as shown in Fig. 13. This view also shows a resilient abutment pad 215 for the blade 180 secured to the support by the screw 163, with which the terminal 161 is fastened to the support.

Wound about the strip 207 is the winding 216 of the safety heater 56, connected at one end to the lead 55 and at the other to the wire 57. A band of insulation 218 is interposed between the strip 209 and the extension 175 of the terminal 158.

A pivotal mounting for the scavenger warp switch mechanism 58 is also provided on the support. Included are a pair of apertured bosses 220 and 221, which project rearwardly and receive the ends of a pivot pin 222. The assembled scavenger switch is of generally U-shaped configuration in end elevation, and includes a base member 224 provided with a pair of spaced upstanding apertured ears 225, through which the pin 222 extends. The member 224 is also provided with a pair of upstanding extensions 226 and 228, as best seen in Fig. 6.

To the forward extension 226, there is attached, by rivets 229, a further upwardly extending blade 230, the upper end of which carries a contact 232 and an angularly contoured member 233. Embedded in the support 141 is a magnet 235, as shown in Fig. 11. The magnet normally biases the blade 230 rearwardly to bring the contact 232 into engagement with a contact 236 on the upper end of a blade 237 secured to an extension 238 of the terminal 160.

Also attached to said support, by a rivet 239, and extending therefrom laterally to the left, is an abutment strip 240 for the member 233 when it moves forwardly to disengage the contacts 232 and 236 under conditions set forth in the co-pending application.

The blade 230 also carries a right-angular fibrous element 245, the horizontal portion 246 of which extends through a vertical slot 248 in the blade 173, and the upstanding portion 249 of which is in engagement with the front face of said blade. The horizontal portion 246 of said member is rigidly attached to a depending flange 250 of the element 233 by a rivet 251.

To the rearward upstanding extension 228 of the scavenger switch base member 224, there is attached, by rivets 256, a further upwardly extending strip 258 of bimetal, the upper end of which is bifurcated as at 259, and a pliant strip of insulation 260.

The strip 260 is provided with a pair of spaced terminals 262 and 263, to which are soldered or otherwise permanently attached the ends of the scavenger heater winding 265, which is coiled about a non-conductive wrapper 267 surrounding the strip 258.

As may be seen by referring to Figs. 9 and 11, a threaded stud 270, embedded in a rearwardly projecting boss 271 of the support, extends through the bifurcation 259. An abutment in the form of a nut or the like 272 is affixed to the projecting end of the stud 270, whereby movement of the strip 258 is limited in a rearward direction. A manually rotatable nut 274 is

provided to limit the movement of said strip in a forward direction.

Obviously, this arrangement provides a ready adjustment for regulating the operational movements of the scavenger warp switch in accordance with the requirements of the copending burner control system.

In view of the foregoing, it should be manifest that the objectives of the invention are attained. A compact assembly is provided in the form of a receptacle which contains not only a number of conventional elements associated with the burner control system of the character under consideration, but which additionally includes novel supporting means for those mechanisms which are most critical in the successful operation of said system.

The advantages inherent in the unitary support whereon said critical mechanisms are mounted, and the facilities provided whereby said support may be quickly installed or removed from the panel of the receptacle, should also be apparent.

It is, of course, understood that, in a mechanism of the type illustrated, structural modifications may be made by those skilled in this art without departing from the spirit of the invention. Therefore, the scope of this invention is to be limited only by the claims.

What is claimed is:

1. In combination, a base, a pair of power terminals on the base, a first set of a pair of accessory terminals on the base, a second set of three accessory terminals on the base; a main relay coil on the base, an armature displaced by energization of the coil, an electrical power reducing means on the base for the relay coil adapted to reduce the power of the main coil to below that required to displace the armature but above that required to hold the armature once it is displaced by the main coil; a safety relay on the base, of the time delay type, having a switch and an energizing means energizable to open the relay switch; a scavenger relay on the base of the time delay type having a switch and an energizing means energizable to open the switch; first circuit branch connections connecting in series the power terminals, the first accessory terminals, the scavenger relay switch, the safety relay energizing means, a first and second of the three second accessory terminals, the safety relay switch, and the main relay coil; second circuit branch connections connecting in series the power terminals, the first accessory terminals, the scavenger relay energizing means, the power reducing means, the second and third of the second accessory terminals of which one is not common to the first circuit branch, the safety relay switch, and the main relay coil; the first circuit branch energizing the safety relay energizing means to open the safety relay switch after a predetermined time, but the energization second circuit branch being exclusive of said energizing means, whereby unless the second branch is energized and the first is deenergized, the safety switch will open to prevent energization of either circuit branch.
2. The combination of claim 1 in which the safety relay switch, once opened, remains open upon subsequent deenergization of the energizing means therefor, and means to reclose the same.
3. The combination of claim 1, together with an additional switch connected to be operated concurrently with operation of the scavenger relay switch.

4. In combination, a base, a safety relay on the base, of the time delay type, comprising a relay switch and an operating means therefor; a scavenger relay on the base, of the time delay type, having a relay switch and operating means therefor, one side of the scavenger relay switch being connected with one side of the scavenger relay operating means, the other side of the said relay switch being connected to one side of the safety relay energizing means; a terminal connected with the said one side of the scavenger relay switch, having means for mounting an external connection thereto; a terminal connected with the other side of the safety relay energizing means, having means for mounting an external connection thereto; a terminal connected with the other side of the scavenger relay operating means, having means for mounting an external connection thereto; a terminal on the other side of the safety relay switch, having means for mounting an external connection thereto; the safety switch being of the non-self-closing type, and means for reclosing the safety switch after deenergization of its operating means.

5. The combination of claim 4, together with an additional switch connected to be operated concurrently with the scavenger relay switch, and terminals for said additional switch.

6. In a switch mechanism: a base; a safety switch on the base, comprising a relay having a heater and a heat-responsive relay switch; a scavenger relay on the base having a heater and a heat-responsive relay switch, the scavenger relay switch including a U-shaped member pivoted to the base, with its heater and a heat-responsive leg lying on one side of the base, and the other leg, having switch contact means, lying

along the other side of the base, the safety switch heater and heat-responsive means being on said other side to minimize heat transfer from one heater to the other heat-responsive means; a connection between the scavenger relay switch and the safety heater to put them in series; and means connecting the scavenger heater with one side of the scavenger relay switch.

7. The combination of claim 6, with an additional switch mounted on the base adjacent the scavenger relay switch, and a member connecting the two switches for conjoint operation.

RYDER PRATT.
